UNITED STATES PATENT OFFICE.

TORSTEN ANDREAS FRITHIOFSSON HOLMGREN, OF STOCKHOLM, SWEDEN.

ELECTRICAL HEAT TREATMENT OF MATERIAL.

Application filed October 19, 1921. Serial No. 508,815.

To all whom it may concern:

Be it known that I, TORSTEN ANDREAS FRITHIOFSSON HOLMGREN, a subject of the King of Sweden, residing at Malmkillnadsgatan 54, Stockholm, Sweden, have invented new and useful Improvements in Electrical Heat Treatment of Material (for which I have filed an application in Sweden, No. 5522, filed December 8, 1919), of which

10 the following is a specification.

The present invention has for object a process for the heating of material the electric resistance of which at a low temperature is greater than at the temperature to which

15 it is to be heated, or for the performance of chemical reactions in electric resistance furnaces of the kind where the heating is effected by an electric current supplied to the mass to be heated by means of one or more 20 circuits by means of electrodes the contact surface of which towards the charged mass has the same or nearly the same breadth as the furnace chamber, so as to create one or more reaction zones approximately at right 25 angles to the direction of movement of the mass, through which zone or zones no appreciable part of the charge can pass without being heated to the desired temperature.

By this arrangement unequal heating is obviated, or in other words, the rise of temperature is confined within a certain limit, so that no appreciable part of the mass is heated to a temperature so high as to be injurious to the working of the process.

30 Experience, however, has shown that in certain cases the cold charge which has been fed, for example, into a shaft furnace, owing to the bad conductivity of the material in the cold state has a tendency, so to speak, to press down—or in the case of horizontal furnaces to push forward out of its proper position—the heating zone in the direction in which the charge moves through the furnace and in consequence hereof the rapidity with 45 which the charge moves through the furnace must be limited to the speed conditioned by the amount of heat transmitted to the originally cold charge either by conductivity and radiation in the mass or by its transmission with the gases generated in the furnace.

The object of the present invention is to

eliminate the above-mentioned drawback by introducing a gas suitable for the purpose into the furnace and causing to pass or circulate through the furnace in the opposite direction to the charge, the gas being first heated by the hot charge, which has passed the heating zone whereupon it gives off heat in its turn to the charge just fed into the furnace, so that the charge enters the heating zone, previously heated to a high degree of temperature and consequently is electrically conductive, whereby the aforesaid drawback is entirely or at least partially obviated.

In order to make plain the invention, three forms of a shaft furnace suitable for the performance of the process in question are shown on the appended drawing.

Fig. 1 shows a vertical section of the furnace along the line A—A in Fig. 2, which latter shows a horizontal section along the line B—B in Fig. 1. Figs. 3 and 4 illustrate in a similar manner another form of the furnace. Figs. 5 and 6 similarly show still another form of the furnace. Corresponding parts are designated in the different figures with the same numbers. The invention will be described first with reference to Figs. 1 and 2.

Fig. 1 designates the furnace shaft through whose walls 2 pass the electrodes 3 and 4 serving for the supply or discharge of the electric current. In accordance with the present invention, the breadth of the electrodes is equal to, or nearly equal to, the breadth of the shaft, as is shown in Fig. 2, whereby, as indicated above, a more uniform heating of the charge is attained in the zone corresponding to the electrodes, or in the layer of the charge or mass to be treated, which must pass through the aforesaid zone. According to the form illustrated in the drawing, which is intended for the use of single-phase alternating current (although three-phase alternating current may also be used), the current is supplied or discharged through two electrodes 3, 4, situated at some distance above one another. As it often happens that the mass which is to be treated in furnaces of the kind in question has a greater electric resistance at lower temperature, it may be

2
advisable, as indicated in Fig. 1, to arrange the electrodes so that the distance between the opposite electrodes (belonging to the same group of electrodes) is chosen with 5 regard to this fact, i. e., to arrange the electrodes in such a way that practically an equal amount of energy is consumed at the two pairs of electrodes. For this purpose the furnace shaft, in the form illustrated 10 in Fig. 1, is somewhat narrower at the part where the upper electrode pair 4 is situated than in that part of the furnace where the lower electrodes 3 are located, so that the distance between opposite ends (or contact 15 surfaces) of the electrodes 4 will be less than the distance between opposite ends (or contact surfaces) of the lower electrodes 3, which the mass reaches in a heated condition owing to the action of the current 20 supplied through the electrodes 4. In order to obtain a preheating of the material introduced into the furnace chamber so that it will reach the heating zone or zones in a highly heated condition, a gas suitable for 25 the purpose is according to the present invention introduced into the furnace in such a way, that this gas passes the charge in the direction opposite to the movement of the charge through the furnace, 30 so that, before it reaches the heating zone, the charge meets gases which have passed through one or more heating zones, and thereby has been heated, which gas in its turn gives off heat to the charge before 35 the latter has arrived at the heating zone. The said gas may, for example in the manufacture of cement consist of air, or in the manufacture of graphite consist of carbon monoxide. According to the form of the 40 furnace shown in Figs. 1 and 2, it is provided with two pairs of electrodes arranged above one another, so that two heating zones are formed, though it is obvious that merely one, or else more than two heating zones 45 may be arranged. Gas may be introduced either only under the uppermost heating zone, or merely under the lowest heating zone, or separately under several heating zones at the same time. According to circumstances, gas may be taken from some 50 special reservoir or gas generating apparatus, or, in case air is employed, from the atmosphere, or else, as shown in Fig. 1, an arrangement may be adopted whereby 55 the gas, or part thereof, passing through the furnace shaft, will be caused to circulate through the furnace chamber. According to this form shown by way of example in the drawing, the gas is supplied 60 between the two heating zones or electrode pairs through a pipe 6, which communicates with a pipe 8 issuing from the upper part of the shaft, in which latter pipe are inserted a gas purifier 9 in order to clean the 65 gas from dust and the like and a pump 10,

by means of which the gas can be caused to circulate through the furnace chamber. The pipe 6 is connected—suitably through a pipe 11 passing round the furnace—to a number of nozzles 6¹ debouching into the 70 furnace chamber (and suitably arranged straight under the electrodes), whereby a better distribution of the gas supplied is attained. It is also possible, as indicated in the drawing, to supply the gas in the 75 lower part of the furnace chamber, i. e., under the lowest heating zone, through a pipe 7 and one or more nozzles 7¹ (which may be arranged in the same manner as above described with reference to the nozzles 6¹), which pipe 7 may also by a pipe 12 shown by the dot-and-dash lines be connected to the pump 10. Through the pipe 7 and the nozzles 7¹ either gas taken out from the upper part of the furnace, or else 80 other gas, may be introduced into the lower part of the furnace and be caused to pass through the charge and the heating zones in the manner indicated above, with the object of preheating the charge before it 85 has reached the heating zone, whilst at the same time effecting the cooling of the finished product which may be discharged through some suitable discharging device 90 13. According to the form illustrated in 95 the drawing, the pipe 8 issues from a free space 15 formed in the upper part of the furnace between the masonry and the lower part of the feeding funnel 14, which space is closed at the top by a cover 16 or 100 similiar device.

In the above the invention has been described with reference to a shaft furnace, but it is obvious that it can also be applied to leaning or horizontal furnaces in which 105 the electric heating is effected in the manner above described.

It should be observed that the present invention is based on the idea that the gas blown in will serve to transmit heat from 110 the charge which has passed, or is in the actual heating zones to the charge which is on the way to the heating zone or zones, so that this latter part of the charge, before it reaches the heating zone, has sufficiently 115 high temperature for the normal course of the process and a corresponding electric conductivity.

The invention may naturally also be performed with, for example, two current circuits, which may be arranged so as to pass at right angles to one another, in which case the electric currents may suitably have a mutual phase displacement of 90° and thus 120 together form a so called two-phase current 125 system.

According to the form illustrated in Figs. 1 and 2, it is the end surfaces of the electrodes that form contact surfaces with the charge. According to the form shown in 130

Figs. 3 and 4, on the other hand, the electrodes are arranged in such wise that the contact surfaces with the charge are formed by the opposite side surfaces of the electrode pairs, as indicated in the drawing. In this way the above stated purpose is attained without necessitating the use of electrodes of so large a breadth or cross section as in the form shown in Figs. 1 and 2, which is better adapted for a furnace shaft with a rectangular cross-section area of comparatively small breadth. The form shown in Figs. 3 and 4 is intended to be used for two-phase alternating current, i. e., with a mutual phase displacement of 90° between the currents 3—3' and 4—4', the shaft has a square cross section, preferably with bevelled corners to prevent the mass, on heating, from sticking in the corners of the furnace shaft, and also to prevent the heating of the mass being excessive at the corners, should any part of the current pass in a vertical direction between the different "compartments" of electrodes (the electrode pairs situated above one another). According to the form illustrated in the drawing, the different pairs of electrodes enter at right angles to one another, which also contributes to a more uniform heating of the charge. Obviously, more than two pairs of electrodes may be arranged above one another, and it should moreover be evident that also in the form shown in Figs. 3 and 4 the electrodes may be arranged in such wise that the distance between opposite electrodes in the different pairs of electrodes shall be different, and that in the same furnace one pair of electrodes may be arranged in accordance with Figs. 1 and 2, and another pair of electrodes in accordance with Figs. 3 and 4. According to Figs. 5 and 6, the parts 3¹ of the electrodes 3, which form contact surfaces with the charge, and whose breadth, as indicated by Fig. 5, is of the same or similar breadth as the furnace shaft 1, extend along a greater or lesser part of the height of the furnace shaft, whereby the heating layer or thickness of the zone in the direction of feed of the charge can be varied at will, according to the length of part 3¹ of the electrodes. According to the form shown in outline in the drawing, the electrodes are made in angular-shaped pieces, but it should be manifest that in practice they may be composed of two or more parts, the horizontal part consisting of one piece, and the vertical part of one or more pieces, which are electrically connected to the horizontal parts passing through the masonry. Obviously in this case also two or more pairs of electrodes may be arranged above one another in the manner described above. It is also advantageous, as indicated in Fig. 1, to give the shaft a shape whereby the distance between the opposite parts of the electrodes will be smaller in the upper part of the furnace—where the material is less heated and thus less conductive than in the lower part of the furnace, where the material has a higher temperature and thus is more conductive, whereby a more uniform distribution at different levels in the furnace of the energy supplied is attained.

It may in certain cases be suitable, as indicated in Fig. 5, to arrange in the upper part of the heating zone, where the temperature of the charge is relatively low and its electric resistance thus relatively high, a so-called central electrode 18, i. e., a body of electrically conductive material of a shape suitable for the purpose, with the object of thereby shortening the path of the current through the charge on that level, whereby the supply of energy to the mass in the same level is increased, whence the distribution of temperature in the furnace can be equalized. According to Fig. 5, the central electrode 18 is shown to consist of a body essentially wedge-shaped, which by means of a rod or the like 19, is held suspended in the furnace at the required level.

It should also be understood that the different electrodes may be replaced by a group of electrode pairs coupled in parallel or fed from separate circuits.

Having thus described my invention, I declare that what I claim is:

1. The process of treating material in electric furnaces, which consists in passing the charge of material between electrodes disposed opposite each other and in contact with the charge throughout substantially its entire breadth, supplying an electric current to said electrodes thereby to form at least one heating zone approximately at right-angles to the direction of movement of the charge and extending throughout the entire cross-section thereof, introducing gas into the furnace chamber below the electrodes and passing said gas in the opposite direction from the charge and through at least one heating zone, and conducting said gas into contact with a part of the charge which has not reached the heating zone.
2. The process of treating materials in electric furnaces, which consists in passing the charge of material between electrodes disposed opposite each other and in contact with the charge throughout substantially its entire breadth, supplying an electric current to said electrodes thereby to form at least one heating zone approximately at right-angles to the direction of movement of the charge and extending throughout the entire cross-section thereof, introducing gas into the furnace chamber below the electrodes and passing said gas in the opposite direction to the charge and through at least one heating zone, and conducting said gas into contact with a part of the charge, which

has not reached the heating zone, the electric current serving for generating of the heat being supplied in the form of two-phase alternating current through two or more single-phase circuits arranged above one another, which may have a mutual phase displacement of 90° or approximately 90° .

In testimony whereof I have signed my name to this specification.

TORSTEN ANDREAS FRITHIOFSSON HOLMGREN.
